UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

SEWING MACHINE.

Application filed April 6, 1926. Serial No. 100,938.

This invention relates to sewing machines and more especially to the control or regulation of the thread and the application of tension thereto. In the particular form 5 herein illustrated the invention is particularly adapted to use on shoe stitching machines or similar leather sewing machines using wax thread; for example the shoe stitching machine well known as the welt-and-turn machine, represented for example by the Reece welt-and-turn machine illustrated in Patent Number 1,288,366 of December 17, 1918 and subsequent patents and pending applications, such machine producing 10 chain stitches by the use of curved, hooked needle and cooperating instruments; although the novel features are applicable to other types of shoe or leather stitching machines, or other sewing machines. 15 The general object of the present invention is to improve the handling of the thread in such machines and especially to improve the operation and efficiency of the thread tension control mechanism. A specific object is to provide automatic means for causing the relaxing or substantial release of the 20 tension upon the thread at a certain period in the stitch cycle and in an effective and accurate manner. A further object is to provide a simple and smooth acting mechanism for such purposes. Further objects and advantages of the present invention will be explained in the hereinafter following description of an illustrative embodiment thereof, or will be apparent to those skilled 25 in the art. To the attainment of the objects and advantages referred to the present invention consists in the novel sewing machine and the novel features of combination, arrangement and structure herein illustrated or described. 30

In the accompanying drawings Fig. 1 is a partial right hand elevation of a welt-and-turn stitching machine, showing sufficient of the exterior parts of the machine to afford an explanation of the present invention. 45

Fig. 2 is an opposite or left hand elevation of the same taken partly in section on the line 2-2 of Fig. 3. 50

Fig. 3 is a top plan view showing the main elements particularly concerned with the present invention. 105

Fig. 4 is a front elevation and central

section of certain of the parts shown in Fig. 3. 55

Fig. 5 is a diagram showing the action or movement of certain of the elements, and the coordination thereof with the movements of the needle, looper, take-up and other usual instruments concerned in the formation of stitches. 60

The cycle of stitching operations in a welt-and-turn stitching machine may be substantially as indicated in the diagram in 65 said prior patent, showing the movements of the needle, the looper, the take-up and other instruments. Fig. 5 herein shows the movements of the needle, looper and take-up as I prefer to operate them, and as indicated in pending applications of mine. Thus the needle may be in advancing motion in the part of the diagram marked c' , later retracting at c^2 . The take-up may swing in a manner to give thread during the 70 movement f' , and moving reversely at f^2 will take up the thread, in cooperation with the needle movements. The looper moves to advance adjacent to the needle and thereafter move around the needle so as to place 75 a loop in the barb thereof. The movement of the looper advancing to the needle and drawing thread from the supply is indicated at d' , while in the movement d^2 the thread is being engaged with the needle hook. The usual feed device may advance 80 the work at curved part g' . 85

According to the present invention the operation of such a machine is improved by a complete release or relaxation of the 90 thread tension during the period in which the looper is advancing toward the needle and pulling thread from the supply. At this period in the cycle the thread is apt to break and this invention obviates the difficulty preferably by a complete removal of 95 the tension. The mechanism and action for accomplishing this result will next be described in connection with the diagram of Fig. 5 and the other figures of the drawings. 100

The vertical frame walls 10 and 11 may be the left and right walls corresponding to those shown in the prior patent and applications. The main or stitching shaft 12 has suitable connections to the needle, looper, take-up, etc., such connections including for example a crank 13 formed on the shaft 12. The shaft is journalled in a bearing 14 in the 105

frame wall 11 and may be similarly journaled near its other end. The fixed parts of the machine may include a bearing stud 15 which is shouldered and passes through a 5 collar or lug 16 spacing it from the left wall 10, to which the stud is secured by screw threads as indicated in Fig. 4.

The matter of applying the tension to the thread may be through a grooved thread 10 wheel 17 which is shown mounted to turn freely on the stud 15. As usual the thread may make substantially a complete turn about the wheel, the thread wheel having a friction face or flange 17^a and a felt washer or 15 facing 18 by which frictional pressure may be applied to retard or brake the rotation of the thread wheel and thus apply tension to the thread. A pressure disk 19 is arranged loosely on the stud 15 in a 20 position to bear against the friction flange 17^a of the thread wheel, or rather the friction facing 18 thereof. For purposes later to be described the pressure disk 19 is provided with peripheral ratchet teeth 19^a. 25 Resilient pressure is preferred but instead of applying this directly against the pressure disk 19 the following special arrangement is shown, constituting a feature of the present invention. The pressure shank or rod 20 has 30 mounted at its left end a pressure ring 20^b which is constantly thrust to the left, but with a thrust bearing or rolling element 20^a between the pressure ring 20^b and the pressure disk 19. Ordinarily this would impose 35 no resistance to the rotation of the thread wheel, but when the disk 19 is anchored against rotation the frictional braking action upon the thread wheel is put into force, as will be described. 40 The pressure shank 20 is shown as extending through the frame right wall 11, its outer end provided with a forked head 21. The shank or rod 20 is shown surrounded by a threaded sleeve 22 which engages threads 45 in the frame wall 11 and is provided with an exterior head 23 by which the sleeve may be turned so as to adjust it longitudinally and regulate the normal degree of tension or spring pressure on the thread wheel. The 50 tension spring 24 surrounds the shank 20 between the elements 20^b and 22. This spring is under constant compression and presses leftward against ring 20^b which in turn, through the antifriction bearing 20^a, 55 applies pressure to the disk 19, thrusting toward the thread wheel. An exterior hand lever 25 is shown in Fig. 1 which may be swung to pull outwardly upon the pressure shank 20 and thereby release the tension at 60 will. An automatic release of the tension when the needle is retracted and the work is being fed along may be effected through the following mechanism, described in a copending application, and per se forming no part 65 of the present invention. A rock lever 26 is mounted on a pivot pin 27 supported in a bearing lug 28 at the outside of the frame wall 11. The rock lever has a forked extension 29 embracing the shank 20 and bearing against its head 21. When the rock lever 70 is swung outwardly this moves the shank and releases the tension. The swinging lever 26 has upstanding ears 30 and 31 through which is engaged a pin 32 adapted to be pushed or pressed to the right by swinging 75 the lever 26. The actual swinging movement may be very slight in order to release the tension for the purposes stated. For this purpose a push rod 37 is shown having a slotted outer extremity, the slot engaging 80 the push pin 32. This motion may be effected through an eccentric by the following mechanism. A large helical gear 39 is shown mounted on the main shaft 12. This engages a helical gear 40 arranged on a 85 short shaft 41 set at right angles to the main shaft and supported in front and rear bearings 42 and 43. The ratio of the gears may be one to one so that the gear 40 makes one rotation for each turn of the main shaft, 90 corresponding with a stitching cycle. At the front side of the gear 40 is shown an eccentric 44 engaged by a strap 46 united with the push rod 37, so that the operation of the eccentric may cause the relaxing of the 95 tension at a point corresponding with the termination of a stitch cycle. Instead of having this relaxation of the tension occur in every stitch cycle it is sometimes sufficient to omit it except at the end of the final 100 stitch cycle when stopping the machine, thus permitting the work and thread to be drawn away from the machine. This it is proposed to accomplish by a particular arrangement between the thrust rod 37 and the eccentric 105 44, for example a roller instead of a strap at the end of the thrust rod, with a pedal connection moving the roller into the path of the eccentric when the pedal is let up to stop the machine, so the rod will swing lever 110 26 and remove the pressure.

The pressure disk 19 intermediate the tension wheel flange 17^a and the pressure ring 20^b has been referred to as provided with ratchet teeth 19^a around its periphery. Under the normal condition of the tension the intermediate disk 19 is anchored by means of the ratchet teeth and a pawl 55, which however is shown lifted or disengaged in Fig. 2. When the pawl is engaged 115 against a ratchet tooth the intermediate disk 19 is prevented from rotation. It therefore imposes resistance to the thread wheel, under the pressure of the tension spring 24. The lifting of the pawl 55 wholly releases the 120 resistance, that is substantially so, the collar 16 being preferably of antifriction metal, and the disk 19 being engaged by a roller bearing. 125

The pawl 55 is shown attached to a short 130

rockshaft 56 mounted in bearings 57 above the tension devices, with a special bracket 58 holding these parts. For the purpose of lifting and lowering the pawl at the proper points of time there is shown a rocker arm 59 on the rock shaft 56, the extremity of this arm having finger 60 which extends downwardly into the path of a lifting pin or contact 61 mounted at the rear face of the gear 40. As the rotation of the gear brings the pin 61 toward its upper position the pin will contact and lift the finger 60 and thus raise the pawl and release the tension, while as soon as the revolving pin passes from under the finger 60 the pawl will be dropped in position to engage the shoulder of the next ratchet tooth.

The preferred timing of the described parts, and the resulting action, may be described in connection with the diagram Fig. 5, which has already been described in relation to the movements of the needle, take-up and looper. While the looper is moving along the path α' and approaching the needle 25 it is drawing thread from the supply, and it is desired to release the tension for this portion of the cycle, as already explained. About the time this thread pulling movement of the looper commences the pawl 55 is 30 to be lifted from the ratchet. The path α' on the diagram shows the position of the pawl engaged upon the ratchet. The path α^2 indicates the lifting of the pawl by the finger 61, and it will be seen that this immediately 35 precedes the thread pulling movement of the looper. The pawl is then lowered or restored along the path α^3 , but does not become effective to lock the ratchet and thus apply full tension, until contacting the next ratchet tooth, indicated at α^4 on the diagram, the 40 looper at this time having finished its thread pulling movement and being about to lay the thread on the barb of the needle.

As the lifting pin lifts the finger and pawl, the thread then being under tension, the thread wheel will at once move freely forward by the thread pull, so that the finger can be immediately dropped upon the next ratchet tooth. Each tooth is preferably of 45 such length as to correspond with the amount of rotation of the thread wheel necessary to supply the thread pulled by the looper, so that the tension is released during such thread-pulling movement, the pawl then 50 coming into contact with the next tooth shoulder and applying the full tension. This all occurs when the needle is forward, through the work, and the full tension, suspended for part of the looper movement, is 55 reapplied before the take-up and stitch setting operations occur.

It will be understood that in the welt-and-turn stitching machine, for which the illustrated embodiment is especially designed, 60 the needle is a curved hook needle which

penetrates the work on its advance stroke and at its advanced position is supplied with a loop of thread by the movements of the looper, the needle then retracting, and being near its fully retracted position when the work is fed by the usual or other feed means. The general operation of the present invention is to relax or release the tension while the looper is pulling thread from the supply to apply to the needle, and fully restoring 75 the tension for the subsequent take-up action; stated in another way the tension resistance is suspended to facilitate the looper movement. It will be noticed that the removal of the tension is not merely for 80 a predetermined part of the cycle in point of time, but is during the pulling by the looper of a predetermined length of thread. The ratchet wheel is designed with teeth of 85 length corresponding with the thread pulling movement of the looper. When the pawl is lifted from the ratchet the thread wheel is released but the pawl is restored on top of the next tooth. As soon as the looper has pulled the predetermined amount of 90 thread, this, through the turning of the thread wheel, and the ratchet wheel, brings the next tooth shoulder up to the pawl, and thus terminates the suspension of the tension resistance. Thus as stated the removal of 95 tension is for a predetermined length of thread drawn. In practise the ratchet tooth may be caused to meet the pawl slightly before the looper has completed its thread drawing movement, as a slight 100 stretching of the thread can be allowed for. Another point of novelty involved in the present invention is that the tension is released without the withdrawing or relaxing of the spring pressure. This is due to the 105 fact that the friction member or disk 19, while constantly subjected to the pressure of the tension spring, is able to be anchored or locked to a stationary part, to impose friction on the thread wheel, or rendered free to 110 remove the tension. The friction disk is squeezed between the thread wheel and the pressure member or ring, with an antifriction device or ball bearing between the disk and ring. In one sense the friction disk is 115 a revoluble brake which is normally anchored, locked, or held against rotation so as to impose frictional resistance upon the thread wheel, or to be rendered free or released for rotation to remove the resistance. 120 By a ratchet, in connection with the friction disk, is intended any equivalent series of teeth or projections cooperating with a suitable pawl or dog which may be applied to and removed from the teeth.

There has thus been described a sewing machine, of the class referred to, embodying the principles and attaining the objects of the present invention; but as various matters of combination, arrangement and structure 125

may be modified without departing from the principles involved, it is not intended to limit the invention to such matters except so far as set forth in the appended claims.

5. What is claimed is:

1. In a hook needle sewing machine, a revoluble thread wheel, a revoluble friction mem-
10 gagement with the thread, a revoluble fric-
tion member contacting the thread wheel
15 with substantial friction, a non-revoluble
presser member pressing said friction mem-
ber against the thread wheel, with an anti-
friction rolling-element bearing between the
presser member and friction member, means
15 anchoring the friction member against ro-
tation during part of each stitch cycle to
impose full resistance on the thread wheel
and full tension on the thread, and timed
means operating to release the friction mem-
20 ber thereby to relax the tension during an-
other part of each stitch cycle.

2. In a hook needle sewing machine, a rev-
oluble thread wheel, a revoluble fixing mem-
ber contacting the thread wheel, means con-
25 stantly pressing said friction member to-
ward the thread wheel, means for anchor-
ing and releasing the friction member com-
prising tooth projections around the fric-
tion member spaced according to the length
30 of thread to be pulled in each cycle, and a
dog arranged to engage said teeth to an-
chor the friction member, and to disen-
gage and reengage the same to permit a
given length of thread to be pulled from the
35 supply corresponding with the tooth spacing,
and timed means controlling said dog.

3. A sewing machine as in claim 2, and
wherein the friction member teeth constitute

a ratchet having individual teeth of an ex-
tent corresponding to the required length of 40
thread to be pulled during the release of ten-
sion, and the dog controlling means acting
to lift the dog from a tooth at the commence-
ment of the pulling action and drop it upon
the next tooth, the tooth-extent determining 45
the length of thread pulled.

4. In a hook needle sewing machine, a
revoluble thread guide, a friction member
constantly pressed against the guide, means
50 normally anchoring the friction member and
imposing full tension on the thread, and
timed means operative during the pulling of
thread from the supply for releasing the
friction member and thereby suspending
55 the tension for a predetermined length of
thread pulled, comprising a ratchet each
tooth of which corresponds in length with
the thread to be pulled, a pawl, and timed
means for shifting the pawl from one tooth
60 to the next tooth.

5. In a hook needle sewing machine, a
thread wheel having non-slipping engage-
ment with the thread, friction means nor-
mally imposing high resistance upon the
thread wheel, and timed means relaxing such 65
resistance for the thread drawing action and
restoring such resistance after a predeter-
mined length of thread has been drawn, com-
prising a ratchet each tooth of which cor-
responds in length with the thread to be 70
pulled, a pawl, and timed means for shift-
ing the pawl from one tooth to the next
tooth.

In testimony whereof, I have affixed my
signature hereto.

JOHN ROGER OLIVER.
